UNITED STATES PATENT OFFICE

157,212

TOWEL RACK

Joseph Stefan, Oaklawn, Ill.

Application November 22, 1948, Serial No. 149,767

Term of patent 14 years

(Cl. D33—16)

To all whom it may concern:

Be it known that I, Joseph Stefan, a citizen of the United States, residing at Oaklawn, in the county of Cook and State of Illinois, have invented a new, original, and ornamental Design for a Towel Rack, of which the following is a specification, reference being had to the accompanying drawing, forming a part thereof.

Fig. 1 is a top plan view of a towel rack, showing my new design;

Fig. 2 is a front elevational view thereof;

Fig. 3 is a right end elevational view of Fig. 2;

Fig. 4 is a left end elevational view of Fig. 2; and

Fig. 5 is a fragmentary bottom view of Fig. 2.

Contrasting appearance is represented by the stippled and the non-stippled areas on the drawing.

I claim:

The ornamental design for a towel rack, as shown and described.

JOSEPH STEFAN.
